(57) CLAIM

The ornamental design for a locking rod device, as shown and described.

DESCRIPTION

FIG. 1 is a perspective view of a locking rod device showing my new design with the lock head to the left;

FIG. 2 is a perspective view of a locking rod device with the lock head to the right;

FIG. 3 is a side view.

FIG. 4 is a side view showing $\frac{1}{4}$ turn clockwise rotation of FIG. 3.

FIG. 5 is a side view showing $\frac{1}{4}$ turn clockwise rotation of FIG. 4.

FIG. 6 is an end view from the non-locking side.

FIG. 7 is an end view from the locking head side.

FIG. 8 is a side view with the lock in the unlock position.

FIG. 9 is a side view showing a second embodiment of the locking rod device.

FIG. 10 is a side view showing a third embodiment of the locking rod device.

FIG. 11 is a side view showing a fourth embodiment of the locking rod device.

FIG. 12 is a side view showing a fifth embodiment of the locking rod device; and,

FIGS. 9-12 disclose different sizes and lengths of the lock rod device, which can be connected to the ornamental end portions disclosed in FIG. 1-8.
